CURTAIN

Harold Holt, Philadelphia, Pa.

Application July 22, 1933. Serial No. 681,784

9 Claims. (Cl. 156—10)

This invention relates to new and useful improvements in curtains and more particularly to the means for suspending the same from the overhanging rods or poles of shower baths and the like.

The principal object of the invention is to provide a curtain of the character set forth having a plurality of supporting devices integral therewith.

10 Another object of the invention is to provide a curtain of the character set forth wherein the integral supporting devices are covered with the same material comprised in the curtain proper.

15 Another object of the invention is to provide a curtain having integral supporting devices adapted for releasable engagement with the pole or rod supporting said curtain.

Another object of the invention is to provide 20 a curtain as set forth having integral supporting devices of durable construction and capable of relatively noiseless operation.

These and other objects as well as certain other features and details of construction of the 25 invention are set forth hereinafter and disclosed in the accompanying drawing, in which:

Fig. 1 is a fragmentary view in perspective of the device forming the subject of this invention, and

30 Fig. 2 is a view in line 2—2, Fig. 1.

Heretofore the majority of shower bath curtains have been provided with a plurality of eyelets at the upper edge thereof and these curtains have been suspended from the shower rod or pole by means of a number of independent hook or other supporting elements which slidably engage said pole and are provided with upwardly extending portions arranged to engage the eyelets of the curtain and support the same. These 35 supporting hooks are for the most part metal constructed in such a manner that when the curtain is pushed to one side of the shower rather suddenly one or more of the curtain eyelets often becomes disengaged from its hook, causing considerable annoyance. In addition these hooks 40 very often make an unpleasant squeak or other noise as they move longitudinally on the support pole when the curtain is pushed aside scratching or otherwise marring the pole, and generally detract from the appearance of the wash room.

50 By the present invention a shower curtain having integral support devices is provided whereby the above undesirable features present in similar devices available heretofore, are eliminated.

55 Referring now more particularly to the drawing the reference numeral 1 designates a curtain fabricated of suitable waterproof material to render the same available for use in conjunction with shower baths and the like. The curtain 60 is provided with a relatively deep hem 2 at its

upper edge and this hem may be formed from a separate piece of the same material as the curtain or the upper edge of the curtain proper as may be desired. In the drawing the hem 2 is shown as made from a separate piece of the material and comprises three thicknesses a, b and c, the edges of which are folded in at the top and bottom respectively as at d and e. The hem may at this time be pinned or otherwise secured to the curtain but the same should not yet be stitched or otherwise permanently secured.

A number of supporting devices or hooks 3 are provided and each of these hooks comprises a relatively rigid member 4, preferably of spring steel or other non-tarnishable metal but may be otherwise, the former being desirable so the end of the hook portion 5 may be bent or curved inwardly in the direction of the shank 6, so that said hook may be normally retained on a supporting rod or pole 7 but may, when deliberately intended, be removed therefrom with but little effort.

The hook 3 is covered in the present instance with one or more thicknesses of material 8 the same as comprised in the curtain 1 and hem portion 2 and it will be noted that this covering extends as a skirt beyond the end of the shank 6 of the metal element 4 a distance approximately equal to the depth of the hem 2 of the curtain, the purpose of which will be set forth hereinafter.

The inner or pole contacting surface of the supporting device 3 is covered with a layer of material 7 such as tape having a relatively heavy rough texture designed to resist wear resulting from friction caused by said device sliding on the shower rod or pole 7 as the curtain 1 is pushed from side to side. This heavy material 9 also acts to eliminate any noise resulting from this sliding contact of the supports 3 on the supporting pole. The coverings on the metal element 4 are stitched or otherwise permanently secured as at 10 to position said element firmly therein.

The covered supporting devices 3 are inserted between two of the hem thicknesses from the outer edge thereof at equally spaced intervals, the entire depth of said hem. It has been previously stated that the skirt of the covering 8 extends a distance equal to the depth of the hem 2 beyond the shank 6 of the metal element 4 and therefore said shank portion will not enter the hem but terminate immediately adjacent the upper edge thereof.

The curtain 1, hem 2 and supporting devices 3 are made integral by stitching or otherwise permanently secured as at 11 longitudinally of the hem 2 adjacent the upper and lower edges thereof, as shown in the drawing.

A shower curtain made in accordance with this invention is complete in itself and may be hung without the usual bother of obtaining sep-

arate hooks therefor. The covering for the supporting devices, the hem, and curtain should normally be of the same color and material to render uniformity to the device and add to the general appearance of the room.

While the present invention has been described specifically as for use in conjunction with shower baths it is not intended that the same be limited thereto but may be embodied in the construction of curtains for use in other instances within the scope of the appended claims.

1. A shower bath curtain adapted for suspension from a horizontal rod, said curtain comprising a sheet of water-impenetrable material having a relatively deep hem at its upper edge, a plurality of supporting means for suspending said curtain from the rod, each of said means including a relatively stiff flexible member, a covering therefor, said covering extending beyond one

end of said supporting means in the manner of a skirt a distance at least as great as the depth of the hem, a relatively heavy tape overlying the inner rod-contacting surface of said supporting means to resist wear and effect noiseless movement of said means on the rod, and means adjacent the longitudinal edges of the hem permanently securing said supporting means to said hem at substantially equal intervals therealong.

2. A curtain adapted for suspension from a horizontal rod, said curtain comprising a sheet of material having a relatively deep hem at its upper edge, a plurality of supporting means for suspending said curtain from the rod, each of said means including a relatively stiff flexible member, a covering therefor, said covering extending beyond one end of said supporting means in the manner of a skirt a distance at least as great as the depth of the hem, a relatively heavy tape overlying the inner rod-contacting surface of said supporting means to resist wear and effect noiseless movement of said means on the rod, and means adjacent the longitudinal edges of the hem permanently securing said supporting means to said hem at substantially equal intervals therealong.

3. A curtain adapted for suspension from a horizontal rod, said curtain comprising a sheet of material having a relatively deep hem at its upper edge, a plurality of supporting means for suspending said curtain from the rod, each of said means including a relatively stiff member, a covering therefor, wear-resisting means overlying the inner rod-contacting surface of said supporting means, and means adjacent the longitudinal edges of the hem permanently securing said supporting means thereto at substantially equal intervals.

4. A curtain adapted for suspension from a horizontal rod, said curtain comprising a sheet of material, a plurality of supporting means for suspending said curtain from the rod, each of said means including a relatively stiff member, a covering therefor, wear-resisting means overlying the inner rod-contacting surface of said supporting means, and means permanently securing said supporting means to the sheet at substantially equal intervals.

5. A shower bath curtain adapted for suspension from a horizontal rod, said curtain comprising a sheet of water-impenetrable material having a relatively deep hem at its upper edge,

a plurality of supporting means for suspending said curtain from the rod, each of said means including a relatively stiff flexible member having a rod-engaging portion and a shank, the extremity of said rod-engaging portion being curved in the direction of the shank, whereby said supporting elements are releasably maintained on said rod, a covering therefor, said covering extending beyond one end of said supporting means in the manner of a skirt a distance at least as great as the depth of the hem, a relatively heavy tape overlying the inner rod-contacting surface of said supporting means to resist wear and effect noiseless movement of said means on the rod, and means adjacent the longitudinal edges of the hem permanently securing said supporting means to said hem at substantially equal intervals therealong.

6. A curtain adapted for suspension from a horizontal rod, said curtain comprising a sheet of material having a relatively deep hem at its upper edge, a plurality of supporting means for suspending said curtain from the rod, each of said means including a relatively stiff member having a rod-engaging portion and a shank, the extremity of said rod-engaging portion being curved in the direction of the shank, whereby said supporting elements will be releasably maintained on said rod, a covering therefor, wear-resisting means overlying the inner rod-contacting surface of said supporting means, and means adjacent the longitudinal edges of the hem permanently securing said supporting means thereto at substantially equal intervals.

7. A shower bath curtain adapted for suspension from a horizontal rod, said curtain comprising a sheet of water-impenetrable material having a hem at its upper edge, a plurality of supporting means for suspending said curtain from the rod, each of said means including a relatively stiff flexible member, a covering therefor, said covering extending beyond one end of said supporting means in the manner of a skirt a distance at least as great as the depth of the hem, and means permanently securing said supporting means to said hem at substantially equal intervals.

8. A curtain adapted for suspension from a horizontal rod, said curtain comprising a sheet of material having a hem at its upper edge, a plurality of supporting means for suspending said curtain from the rod, each of said means including a relatively stiff member, a covering therefor, and means permanently securing said supporting means to the hem at substantially equal intervals.

9. A curtain adapted for suspension from a horizontal rod, said curtain comprising a sheet of material having a relatively deep hem at its upper edge, a plurality of supporting means for suspending said curtain from the rod, each of said means including a relatively stiff member having a rod-engaging portion and a shank, the extremity of said rod-engaging portion being curved in the direction of the shank, whereby said supporting elements will be releasably maintained on said rod, a covering therefor, and means adjacent the longitudinal edges of the hem permanently securing said supporting means thereto at substantially equal intervals.

HAROLD HOLT.
